UNITED STATES PATENT OFFICE.

ARTHUR THOMAS, OF THORNTON HEATH, ENGLAND, ASSIGNOR TO THE ACCOUNTING & TABULATING CORPORATION OF GREAT BRITAIN, LIMITED, OF LONDON, ENGLAND.

CARD-DELIVERY MECHANISM.

Application filed October 17, 1927. Serial No. 226,760.

The invention relates to card-delivery mechanism and is particularly applicable, through not restricted, to the delivery mechanisms of statistical, calculating and like machines, in which perforated cards are used. Such machines may deliver three or four hundred cards a minute and the receptacle into which they are delivered thus rapidly becomes filled; at such high speeds, apart from the close attention required, difficulty is experienced by the operator in clearing the receptacle without interfering with the continuous action of the machine. The present invention seeks to overcome such difficulties by the provision of a plurality of card receptacles associated with appropriate change-over mechanism.

Referring to the accompanying drawings which illustrate one form of the invention:—

20 Figure 1 shows a general view of the delivery mechanism and card receptacles; Figure 2 is a cross-section on the line 2—2 of Figure 1 showing the change-over mechanism, while

25 Figures 3, 4 and 5 show different positions of such mechanism.

According to the form shown, the main motion shaft, A, of the machine such as a calculating machine from which the cards are delivered drives the feed rolls, B, B, continuously and also the rolls, C, C, which by their rotation tend to press a card, D, against the stop, F, such a card being shown in the sensing pin-box forming a feature of certain calculating machines. By means of the eccentric, G, and the eccentric rod, H, the pin-box and stop, F, are reciprocated up and down in a vertical direction. A pin, J, forming part of the reciprocating system oscillates a lever, K, about the fixed centre L this lever serving to operate the change-over mechanism in a manner to be described.

The cards are delivered into one or other of two receptacles, M, N, as required, a fixed diverter, N', ensuring that if the cards pass over the box, M, they will be turned down into the box, N. The box, M, however, is provided with a movably-mounted diverter, M', such that when in the down position

shown in Figure 1 cards will pass over it to 50 be deflected by the diverter, N', into the box, N, whereas in the up position shown in Figure 4, the cards will strike against it and be delivered into the box, M.

The boxes may be of any approved construction and contain trays such as M², N², pressed upwardly by the springs, M³, N³, to take the weight of the cards.

The change-over mechanism itself is designed so that into whichever box the cards 60 are being delivered, operation of the change-over mechanism diverts them into the other box, this operation in addition being so timed as not to interfere with the delivery of the cards from the machine.

According to one form of this change-over mechanism a disc, 2, mounted on the spindle, 3, is rotatable and slidable axially on the bracket, 4, fixed to any convenient part of the frame of the machine. This bracket on 70 one side has six equally-spaced pins, 2^a, at a certain radius from the centre of the disc, while on the other side are arranged three equally-spaced pins, 2^b, at the same radius as the pins, 2^a, and co-axial with three of such 75 pins.

The pins, 2^a, are engaged as hereinafter described by the pawl lever, 5, pivoted on the end of the lever, K, and brought into the extreme position in reference thereto by the 80 spring, 6, as shown in Figure 4. A catch, 7, pivoted to the bracket, 4, at 8, and pulled down by the spring, 9, serves as a detent to prevent rotation of the disc in a rearward direction.

The pins, 2^b, on the other hand co-operate with a lever, 10, pivotally mounted to turn about the centre, 11, and in rigid relation to the diverter, M', the lever being cut away in the region, 12, to form a shoulder or the 90 like with which the pins, 2^b, can engage under the influence of the spring, 13. The disc spindle, 3, carries an operating knob formed of two parts, 14^a and 14^b, screwed together, the knob as a whole being slidable on the spindle, 3, and pressed outwardly by the spring, 15, acting between it and the frame. The knob is made hollow and presses against the

flange 16, on the spindle, 3, a prolongation of which, 3^a, passes through the part, 14^a, of the knob and serves as a guide therefor, a second spring, 17, keeping the knob pressed 5 against the flange, 16.

The operation of the mechanism is as follows:—

If it is desired to change over from either 10 box to the other, the knob is pressed inwards and if, as is probable, the lever, K, is in the position shown in Figure 4, one of the pins, 2^a, will bank against the lever, 5, thereof. As 15 soon as the lever, K, is moved upwardly, however, into or towards the position shown in Figure 1, so that the lever, 5, is carried clear of the disc, under the latter the pressure of the spring, 17, will move inwards to its fullest extent, the next downward movement of the lever, K, causing the pawl lever, 5, to engage with a pin, 2^a, and thus move the disc 20 through 60° in the direction shown by the arrow.

If the diverter, M', is in the position shown 25 in Figure 5, movement of the disc through 60° will cause it to assume the position shown in Figure 4 with the lever, 10, forced to the left and the diverter, M', raised. Alternatively, if the diverter is in the position shown 30 in Figure 4, rotation of the disc through 60° will bring it into the position shown in Figure 5 with the diverter down.

Overrunning of the disc is prevented by the co-action of the appropriate pin, 2^b, with the lever, 10, while backward motion of the 35 disc is prevented by the co-action of the detent, 7, with a pin, 2^a. Owing to the shape of the hooked end, 5^a, of the pawl lever, 5, the disc can only be turned through 60° for any 40 one operation of the knob, for as shown in Figure 5, with the left-hand end of the lever, K, in its uppermost position, this hooked end cannot pass over the neighbouring pin, 2^a, to engage therewith for another stroke, such engagement only being possible when on release 45 of the knob the disc is returned to its non-operative position by the action of the spring, 15. The pawl lever, 5^a, then assumes the position relative to the lever K, shown in Figure 1 and is ready to engage a pin, 2^a, 50 on the next operation of the knob.

No matter, therefore, which receptacle is receiving the cards at a given movement, precisely the same manual operation diverts them into the other receptacle and in addition so times the setting of the diverter as not to interfere with the continuous delivery of the cards.

Although a particular mechanism has been described in detail by way of example, it will 60 be obvious to those skilled in the art that other mechanisms can be employed to perform the same functions and I therefore desire the appendant claims to be read as broadly as the law allows.

Having now described my invention, what

I claim as new and desire to secure by Letters Patent is:—

1. In combination in a card-delivery mechanism of the kind indicated, means for delivering a series of cards; a pair of card receptacles; means for changing delivery from either receptacle to the other; and means movable from the same initial position to the same final position to actuate said delivery-changing means in either direction. 75

2. In combination in a card-delivery mechanism of the kind indicated, means for delivering a series of cards; a pair of card receptacles; means for changing delivery from either receptacle to the other, said means including a diverter movable between two extreme positions; and means movable from the same initial position to the same final position to move said diverter alternately in opposite directions between the said extreme 80 positions thereof.

3. In combination in a card-delivery mechanism of the kind indicated, means for intermittently delivering a series of cards; a pair of card receptacles; a card diverter 90 movable between two extreme operative positions to change delivery from either receptacle to the other; means for operating said diverter in timed relation to said intermittently-delivering means, said diverter-operating means including a timed member having an alternating movement; means for bringing said diverter-operating means into action; and means for preventing more than one movement of said diverter between its extreme operative positions notwithstanding a plurality of alternating movements of said timed member. 100

4. In combination in a card-delivery mechanism of the kind indicated, means for intermittently delivering a series of cards; a pair of card receptacles; a diverter for changing delivery from either receptacle to the other; a member having an alternating movement in timed relation with said intermittently-delivering means; a movable diverter actuator; and means for moving said diverter actuator into and out of engagement with said member having an alternating movement. 105

5. The combination of parts claimed in claim 4, in which the diverter actuator takes the form of an axially-movable disc carrying two series of pins, of which the pins in one series actuate said diverter and the pins in said other series are engaged by said member having an alternating movement. 110

6. The combination of parts claimed in claim 4, in which the diverter actuator takes the form of an axially-movable disc carrying a series of equally-spaced pins, while the member having an alternating movement consists in a pivoted pawl lever engageable with a pin of said series to perform an operative stroke in one direction but shaped to pre- 115 120 125 130

vent engagement with an adjacent pin on the return stroke.

7. In combination in a card delivery mechanism of the kind indicated, means for successively delivering a series of cards; a pair of card receptacles; means for changing delivery from one receptacle to another in timed relation to the delivery of said cards;

and an instrumentality for bringing said delivery-changing means into operation in such 10 timed relation independently of the moment of operation of said instrumentality.

In testimony whereof I have signed my name to this specification.

ARTHUR THOMAS.
